ATTORNEYS

UNITED STATES PATENT OFFICE.

AUSTIN KANZEE, OF BERKELEY, CALIFORNIA.

DESIGN FOR A TIRE.

52,703.

Specification for Design.

Patented Nov. 19, 1918.

Application filed December 27, 1917. Serial No. 209,180. Term of patent 14 years.

To all whom it may concern:

Be it known that I, AUSTIN KANZEE, a citizen of the United States, and a resident of the city of Berkeley, county of Alameda, State of California, have invented a new, original, and ornamental Design for a Tire, of which the following is a specification, reference being had to the accompanying drawings, forming part thereof.

Figure 1 is a plan view of a portion of a tire illustrating my new design.

Fig. 2 is a cross-section of the tire taken on the line 2—2, Fig. 1.

I claim:

The ornamental design for a tire, substantially as shown.

AUSTIN KANZEE.

Witness:

H. G. PROST.
